ADJUSTABLE HEAD SUPPORT FOR
DISPLAY FORMSRoy A. Schramm and Edmund S. Wisniewski,
Bay City, Mich.

Application February 26, 1944, Serial No. 524,148

1 Claim. (Cl. 223—66)

1

This invention relates to display forms such as used for displaying wearing apparel, and more specifically to a form having a separate head including means for adjusting said head with relation to the form, so that the neck, which is formed integral with the head, may be lowered into the collar of a shirt without the necessity of first opening the collar, or otherwise adjusting or disarranging the wearing apparel to be displayed.

One of the prime objects of the invention is to provide a display form provided with a separate head, and provide means whereby the head may be vertically adjusted with relation to the form, so that when the form is draped or dressed with a shirt, tie, coat and/or other wearing apparel, said head may be lowered to telescope the neck of the form into the collar opening, thus providing a complete display, instead of the headless bust form at present in general use.

Another object is to provide a display form including a separate, vertically adjustable head unit, the support for which is not visible looking from the front of the form; said form being very economical to manufacture and assemble, and also easily and quickly adjustable when the form is being dressed or undressed.

A further object is to provide a display form including a separate adjustable head unit, the support for said unit being connected to the head at a point substantially at the hair line at the back of the neck.

A further object still is to provide a bust display form including a separate, vertically adjustable unit, and with which hats or other articles of personal adornment can be displayed simultaneously with the shirt, coat, or dress which is placed on the form.

An understanding of the invention may be had from the following description, taken in connection with the accompanying drawing in which:

Fig. 1 is a front elevational view illustrating the general appearance of the display form after it has been dressed, with a shirt, tie, and coat, and the neck of the head unit telescoped into the neck of the shirt;

Fig. 2 is a side elevational view; and

Fig. 3 is a view similar to Fig. 1, illustrating the head unit in raised position and swung circumferentially to facilitate easy dressing and/or undressing of the form;

Fig. 4 is an enlarged detail illustrating the telescopic connection and nut lock.

Fig. 5 is a fragmentary view showing the display form.

2

Like reference numerals indicate like parts throughout the several views of the drawing.

The display form 3 can be formed of any desired material, it can be made of papier-mâché, or it can be cast of any suitable material adaptable for the purpose required.

In the instant construction, the form is shown mounted on a post 9 formed with a foot or base 10 to support it in upright position; this can be of any desired shape or ornamentation, and the form can be attached to the upper end of the post in any manner. The bust of the form is of the type at present in general use, and is of a size to accommodate a shirt 11, tie 12, and coat 13, the upper edge of the shirt collar 14 projecting above the upper end of the form to accommodate the neck 15 of the head unit 16 which is adjustably mounted with relation to said bust.

The head unit is mounted for vertical and circumferential adjustment, the neck of the unit telescoping into the collar opening in the shirt 11 when the form is dressed. This head unit 16 is supported on a rod 17, the upper section 18 of said rod being hollow and is attached to the head 25 at substantially the edge of the hair line at the back of the neck. A collar 19 is shrunk on the lower end of the rod 18 as shown and a wing head set screw 20 is mounted therein for rigidly securing it in position.

30 The head unit is supported from the post 9, the rod 17 being clamped to the post at a point directly below the lower edge of the form, thence extending vertically with the end slidably engaging and telescoping in the hollow rod 18, and it will be obvious that by tightening the set screw 20 that the head can be held in any desired position of vertical or circumferential adjustment.

When it is desired to drape or dress the form, the head unit is first raised clear of the collar and 40 is then swung to position to afford unobstructed space to permit the draping or application of the desired articles of wearing apparel to the form, after which the head is swung to proper position and lowered, so that it telescopes into the open neck of the shirt, and when in proper position of adjustment, the wing head screw is tightened to secure the head in set position, and a hat or other article of adornment can be added. It will of course be obvious that the adjustment may be 45 accomplished by sliding the clamp 22 on the post 9 and the nut 23 can be utilized to secure it in adjusted position. We find, however, that the upper joint is more convenient.

This makes a very attractive life-like display 55 in comparison with the headless forms at present

in use for this purpose, it is readily adaptable, it can be merchandised as an entire new display, and it is also adaptable to forms at present in general use, the head unit and its support being clamped to the post of the headless forms.

The fact that it is unnecessary to unbutton the shirt when placing it on the form also is advantageous, inasmuch as it can be readily removed, and upon proper folding is in the same shape and condition that it was when shipped by the manufacturer.

From the foregoing description it will be clearly obvious that we have perfected a very simple, attractive and economical display form of the nature described.

What we claim is:

A display form comprising a body member simulating the upper portion of the human body and over which a closed shirt including its collar may be draped, a post supporting said body member in upright position, a rod extending upwardly, rearwardly of said body member and having the lower end thereof supported by said post, a head and neck unit separate from and disposed above said body member, a member connected to said head and neck unit and movably engaged

with the upper end of said rod for vertical and lateral adjustment of the unit relative to the body member whereby upon vertical adjustment of the unit the neck portion thereof may be moved into and out of the closed collar of the shirt, and upon lateral adjustment the unit may be moved to a position to facilitate draping of the shirt on the body member, and means cooperating with said rod and member for securing the unit in any adjusted position.
